Primary Examiner — Ian Simmons*Assistant Examiner* — Keith Frank(74) *Attorney, Agent, or Firm* — Tucker Ellis LLP; Carlos Garritano(57) **CLAIM**

The ornamental design for a storage container, as shown and described.

DESCRIPTION

FIG. 1 is a perspective view of a storage container showing our new design;

FIG. 2 is a perspective view of the storage container illustrated in FIG. 1 without a pail-type handle;

FIG. 3 is a rear perspective view of the storage container illustrated in FIG. 1 without a pail-type handle;

FIG. 4 is a left side view of the storage container illustrated in FIG. 1 without a pail-type handle, with the right side being a mirror-image thereof; and,

FIG. 5 is a perspective view of the storage container illustrated in FIG. 1.

The broken lines in the drawings showing the storage container illustrate the portions of the storage container that form no part of the claimed designed.
